BELT OR THE LIKE FOR PERSONAL WEAR

Edwin S. Mix, Rochester, N. Y., assignor to
Hickok Manufacturing Company, Inc., Rochester, N. Y., a corporation of New York

Application February 28, 1934, Serial No. 713,398

7 Claims. (Cl. 241—8)

This invention relates to belts or the like for personal wear.

One object of the invention is to provide a belt or the like for personal wear embodying the usual or other end fastening buckle straps with the body of the belt composed of more or less elastic or stretchable material and which may be formed in a single operation.

Another object resides in the provision of a belt or the like for personal wear consisting of a core of elastic material and a covering of extensible interwoven or other extensible fabric material whereby upon stretching of the elastic material the braided or interwoven fabric covering is extended according to the stretch of the elastic material.

With these and other objects in view, the invention consists in the novel construction, combination and arrangement of parts hereinafter more fully described, illustrated in the accompanying drawing, and pointed out in the claims hereto appended, it being understood that various changes in the form, proportion, and minor details of construction, within the scope of the claims, may be resorted to without departing from the spirit or sacrificing any of the advantages of the invention.

In the drawing:

Figure 1 is a perspective view of a belt constructed in accordance with the present invention.

Fig. 2 is a longitudinal horizontal sectional view on the line 2—2 of Fig. 1.

Fig. 3 is a transverse sectional view on the line 3—3 of Fig. 1.

Fig. 4 is an enlarged fragmentary view of the belt with parts broken away to more clearly illustrate the belt body.

Referring now more particularly to the accompanying drawing, the reference characters A and B indicate any suitable type of buckle straps. In the present instance, the buckle strap A is folded intermediate its ends to provide the outer and inner folded portions 1 and 2, respectively. The outer folded portion 1 is shown as being of greater length than the inner folded portion 2 and the inner end of the folded portion 2 is beveled and sewed to the outer folded portion 1 along a transverse line, as indicated at 3.

The folding of the portions 1 and 2 of the buckle strap A results in the formation of a transverse seat 5 adapted to receive the inner connecting end of a buckle 6. The inner end of the buckle is held in said seat by a line of transverse stitching 7 and the bight portion is provided with an opening 8 for the passage of the buckle tongue 8' which may be of any suitable shape or form.

60 The inner end of the longer folded portion 1

of the buckle strap A is slotted or bifurcated as at 9 for a purpose presently explained and the usual belt loop 10 is secured between the outer and inner folded portions 1 and 2 between the lines of stitching 3 and 7, as shown.

65 The buckle strap B is slotted or bifurcated at its inner end, as at 11, for a purpose presently explained and throughout substantially the length of its body this buckle strap B is provided with a plurality of apertures 12 to receive the tongue 8' of the buckle 6 in the usual and well-known manner to secure the belt on the wearer with the buckle strap B passed over the outer face of the buckle strap A through the aforesaid loop 10.

70 The belt body is indicated at C and it is of a peculiar structure, including a core composed of elastic webbing or other suitable elastic material 13 and a covering of extensible interwoven or braided fabric 14. The braided covering consists of interlaced strands arranged diagonally with one set of diagonally disposed strands crossing the other set of diagonal strands and interlaced therewith. These diagonally arranged crossed strands may be of one color or mixed colors, as 75 desired. This covering of interwoven or braided fabric is unattached to the elastic material except at the ends thereof and there only when the ends of the belt body are secured to the belt buckle straps A and B. Both edges of the elastic material are rough, as indicated at 15, and the edges of the fabric covering have a tight engagement with the rough edges of the elastic webbing and longitudinal creeping of the flexible fabric covering on the core is thereby prevented. The elastic webbing and the interwoven covering are of substantially the same 80 length and under the influence of a stretching action on the elastic webbing the interwoven fabric covering becomes extensible according to 85 the degree of stretch of the elastic core.

85 The core and braided covering are not made as separate units and then brought together. On the other hand, the braid is applied over the core by a machine in one operation.

90 Care is exercised with regard to the tension used in the braiding operation so as to draw the braid snugly over the edges of the core to prevent the shifting of the braid along the core while the belt is being worn or stretched. There 95 is a rather free mounting of the flat sides of the braided covering on the flat elastic sides of the webbing compared with a relatively tight frictional engagement of the braided covering with the rough edges of the elastic webbing. 100 Owing to the interweaving of the strands of the fabric or braided covering the covering is extensible under the influence of varying stretching action on the elastic webbing and the structure of the braided fabric covering is such that 105 110 115 120

the covering narrows with a narrowing of the elastic webbing as the latter narrows under a stretching action and widens to its normal width as the elastic webbing widens upon release of tension thereon.

For ornamental purposes the strands of which the braided fabric is composed may be of various colors with the result that a highly attractive belt results and owing to the single operation or method in producing the body of the belt on the one machine the belt is relatively inexpensive to manufacture.

One end of the belt body is secured by sewing or otherwise, as indicated at 3, in the bifurcation 9 of the buckle strap A while the opposite end of the belt body is secured in the bifurcation 11 of the buckle strap B by sewing or otherwise, as indicated at 16.

The buckle straps and buckle are not the essential features of the present invention. The essential feature of the present invention goes to the stretchable belt body composed of an elastic core such as elastic webbing, and an interwoven or braided extensible covering having non-creeping engagement with the edges of the elastic webbing or core.

The fabric covering, in this instance, is composed preferably of flat strands of relatively soft fabric material of two different or contrasting colors and these strands under the stretching operation are readily extensible. In the belt body illustrated, the strands are so woven and interlaced as to provide alternately diagonally arranged black and silver colored lines 17 and 18, respectively, extending from edge to edge of the belt body on both sides thereof, but it is to be understood that other color schemes may be adopted or a solid color employed. The pitch or angle of the diagonal strands 17 and 18 is considered essential to effective extensible operation of the covering with relation to the stretch of the elastic webbing.

If the belt body is stretched the diagonally disposed fabric strands extend slightly by reason of the stretching of the belt body and these strands retreat to normal position when the stretch is released. In other words, in accordance with the stretch of the elastic webbing the diagonal strands give under the pull on the elastic core or webbing but do not expose the latter owing to the opposite diagonal interlocked relation of the strands, concealing the elastic webbing within the covering.

What is claimed is:

1. A belt or the like for personal wear including a flat core composed of elastic material and a covering of extensible braided fabric free of the faces of the elastic material lengthwise along the latter between the ends thereof, and along both edges of the elastic material having tight frictional engagement therewith throughout the length thereof so as to thereby render the covering extensible under the influence of a stretching action of the elastic material.

2. A belt or the like for personal wear including a flat core composed of elastic webbing and a covering of interwoven strands of fabric free of the faces of the elastic webbing lengthwise along the latter between the ends thereof and which webbing and fabric covering are of

substantially the same length, the covering having relatively tight frictional engagement with the edges of the elastic webbing whereby the covering is readily extensible under the influence of a stretching action on the webbing.

3. A belt or the like for personal wear including a belt body composed of a strip of flat elastic webbing and a covering of extensible material composed of closely interwoven diagonally disposed narrow strands of material formed over the elastic webbing and free of the flat faces of the elastic webbing between the ends thereof and having tight frictional engagement with the edges of the elastic webbing, the strands of the interwoven material being loosely arranged along the inner and outer flat faces of the elastic webbing.

4. A belt or the like for personal wear including a belt body composed of a flat strip of thin elastic webbing and a covering of extensible material covering the elastic webbing and composed of interwoven diagonally arranged strands of fabric material free of the side faces of the webbing between the ends of the latter and having relatively tight frictional engagement with the edges of the elastic webbing whereby the covering is extensible upon stretching of the elastic webbing, and fastening means secured to the ends of the said belt body.

5. A belt body composed of a flat strip of elastic webbing having roughened longitudinal edges and a covering of extensible material composed of interwoven diagonally arranged strands of fabric material formed over the elastic webbing and free of the sides of the webbing and having a tight engagement with the roughened edges of the elastic webbing whereby the covering is extensible upon stretching of the elastic webbing and the covering maintained against undue creeping with relation to the elastic webbing incident to the tight engagement of the covering with the rough edges of the elastic webbing.

6. A belt body composed of a flat strip of elastic webbing having roughened longitudinal edges and a covering of extensible material composed of interwoven diagonally arranged strands of fabric material formed over the elastic webbing and free of the side faces of the webbing between the ends thereof and having a tight engagement with the roughened edges of the elastic webbing whereby the covering is extensible upon stretching of the elastic webbing and the covering maintained against undue creeping with relation to the elastic webbing incident to the tight engagement of the covering with the rough edges of the elastic webbing, the strands of fabric material being of contrasting colors, and buckle straps secured to the ends of the said belt body.

7. A belt or the like for personal wear including a core composed of elastic material and having a roughened portion, and a covering of extensible braid fabric enclosing the elastic material and having relatively tight connection with the roughened portion of the elastic webbing to prevent creeping of the covering on the elastic material, and buckle straps secured to the ends of the elastic material and the ends of the fabric covering.

EDWIN S. MIX.
